UNITED STATES PATENT OFFICE.

JOSEPH H. SANDERS, OF TRUCKEE, CALIFORNIA.

DESIGN FOR A WATCH-FOB.

42,709.

Specification for Design.

Patented July 2, 1912.

Application filed March 18, 1912. Serial No. 684,642. Term of patent 3½ years.

To all whom it may concern:

Be it known that I, JOSEPH H. SANDERS, a citizen of the United States, residing at Truckee, in the county of Nevada and State of California, have invented a new, original, and ornamental Design for Watch-Fobs, of which the following is a specification, reference being had to the accompanying drawing, forming a part thereof.

The figure is an elevation of a watch fob, showing my new design.

I claim:

The ornamental design for a watch fob, as shown.

JOSEPH H. SANDERS.
